BINDER FOR LEAVES

André Prache, Paris, France

Application May 17, 1939, Serial No. 274,095

8 Claims. (Cl. 281—25)

This invention relates to devices for binding leaves or sheets and particularly to such devices comprising a comb-shaped structure the teeth of which are adapted to be inserted through aligned perforations formed along one of the marginal edges of a pack or bundle of leaves.

The primary object of the invention is to provide an improved binder, wherein the teeth extending from the opposite edges of a strip of resilient material are so arranged that each perforation can be engaged by a pair of teeth juxtaposed side by side but in non-overlapping relation.

Another object of the invention is to provide an improved binder for leaves having marginal perforations, wherein the teeth juxtaposed side by side pairwise extend from staggered positions of the opposite edges of a strip-shaped stock of resilient material and are bent into loops that are engaged through the respective perforations.

Another object again of the invention is to provide an improved binder for perforated leaves or sheets, wherein the free ends of the teeth extend to the neighborhood of the edge of a strip of resilient material opposite to its edge from which they spring out thereby forming complete loops separated by narrow slits.

Still another object of the invention is to provide an improved binder for a pack of perforated leaves, wherein each perforation is engaged by a pair of juxtaposed loops formed by bending round teeth extending side by side in reverse directions from the opposite edges of a strip-shaped stock of resilient material, the free ends of said loops being located at offset positions so that the leaves cannot become unduly disengaged.

A further object of the invention is to provide an improved binder for perforated leaves, wherein the teeth or loops grouped pairwise extend from staggered positions of plain runs of the opposite longitudinal edges of a strip-shaped stock of resilient material, said plain runs being separated by notches into which may project the free ends of each tooth or loop, the slip between each pair of juxtaposed loops extending at any suitable angle to the major axis of the stock, the teeth being of tapered shape and separated in each pair by a helically extending slit, each notch being so sized and formed as to accommodate at least partly the adjacent end of a tooth or loop.

Still a further object of the invention is to provide an improved binder for perforated leaves which can be easily and cheaply made by punching a sheet of any suitable resilient material to

form a comb-shaped blank of the required pattern, the teeth of such blank being afterwards readily bent into loops and engaged in pairs into the respective perforations of a pack of loose leaves or sheets for securely retaining said leaves in bound relation, the tapering shape of the teeth facilitating their insertion through the perforations.

With these and such other objects in view as will incidentally appear hereafter, the invention comprises the novel structure and arrangement of parts that will be now fully described with reference to the accompanying drawing exemplifying suitable embodiments of the same and forming a part of the present disclosure.

In the drawing:

Figure 1 is a plan view of a blank from which the binder according to the invention may be bent and shaped into operative form.

Figures 2 and 3 are views similar to Fig. 1 showing modifications of the blank from which the binder is made.

Figure 4 is an elevational view partly isometric showing a binder according to the invention as applied to a pack of leaves or sheets formed alongside one of their edges with a row of aligned marginal perforations of elongated shape.

Figure 5 is a fragmentary perspective view showing a modification of the binder as applied to a pack or bundle of leaves or sheets.

Like reference numerals designate like parts throughout the several views.

As illustrated in Figures 1, 2 and 3, the binder is made from a flat blank which may be constituted by any suitable thin material, preferably a strip of a more or less hard and resilient material such as a metal or alloy, Celluloid, viscose or the like, such material being either left bare or covered or clad with paint, varnish, fabric or a similar coating. This coating may be of a color matching that of the color of the leaves or contrasting with it. Any suitable ornamentation or inscriptions may be provided on the binder. The leaves may be of uniform or differentiated thicknesses. For instance, the outer leaves of a pack may be of greater thickness than the remaining leaves for affording the required protection of the pack.

As shown in Fig. 1, the strip from which the binder is made comprises a central or stock portion 11 and a plurality of tapered teeth 12, 13 of equal length extending from the opposite longitudinal edges of said stock portion. Intermediate the teeth, each of said longitudinal edges is cut at intervals to provide inwardly tapering 55

notches 14, 15 which are in staggered relation from one edge to the other. The teeth 12, 13 are also arranged in staggered relation, those which extend from one longitudinal edge of the stock 5 portion 11 substantially corresponding in location with the notches cut in the opposite longitudinal edge. In the form shown, one of the free edges of each tooth 12 or 13 is perpendicular to the longitudinal edge of the stock portion 11 while 10 the other free edge of the tooth extends obliquely at an angle to said longitudinal edge. The angle at which run the oblique free edges of all teeth 12 on one side of the stock portion 11 is substantially equal to the angle at which the oblique 15 free edges of all teeth 13 on the opposite side of said stock portion run, but said oblique free edges are slightly offset from any tooth 12 on one side to the nearest tooth 13 on the opposite side. The straight runs 16, 17 of the longitudinal edges 20 of the stock portion 11 between the consecutive teeth 12 or 13 on each side are substantially longer than the widths of the teeth at their base (broader) end.

Owing to this arrangement, when the teeth 25 have been bent round to form loops and the binder is in operative position with respect to the pack of leaves 10 (as shown in Fig. 5) the teeth 12, 13 are grouped pairwise and a narrow slit 18 is defined between each pair of teeth juxtaposed side by side. Each pair of contiguous teeth or loops is engaged in one of a row of aligned marginal perforations 19 formed along the adjacent edges of the leaves 10.

The modification shown in Fig. 2 slightly differs from the form shown in Fig. 1 by the fact that the notches 14 and 15 instead of being sharp have stump or truncated bottoms as shown as 14^a and 15^a and the straight runs 16, 17 on the opposite longitudinal edges of the stock portion 11 are almost equal to the width of the teeth 12, 13 at their base (broader) ends. As a result of this, the teeth are more closely clustered relative to one another. Consequently they can be engaged through closer marginal perforations 45 19 of the pack or leaves 10. As will be seen, in this construction, each tooth 12 forms with the nearest tooth 13 on the opposite edge of the stock portion 11 a parallelogrammic structure.

In the modification illustrated in Fig. 3, the 50 notches 14 and 15 have shapes similar to those shown in Fig. 1 but the free edges of the teeth 12, 13 instead of converging as in Figs. 1 and 2 run parallel to each other over the greater portion of their lengths and are interconnected adjacent 55 their extremities by short oblique lines 12a and 13a forming, as it were, bevels. The obliquity of each line 12a runs, relative to the major axis of the stock portion 11 in a direction reverse to the obliquity of each line 13a, the latter being substantially parallel with the obliquely extending edge of the notches 14 and 15. The teeth 12 and 13 extend from the opposite edges of the stock portion 11 in staggered arrangement, and the straight runs 16 and 17 are about twice 60 as long as the width of each of the teeth.

Instead of having bevelled ends as shown at 65 12a and 13a, the teeth 12 and 13 may have double bevels as illustrated in Fig. 4.

As will be seen, the free end of each tooth 12 70 or 13 projects into one of the notches 15 or 14 formed in the longitudinal edge of the stock portion 11 of the strip opposite to the edge from which the teeth extend. This feature, coupled with the fact that a pair of companion teeth 12, 75 13 defining between them a narrow slit 18 is en-

gaged through each perforation 19, prevents the leaves 10 from becoming unduly disengaged from the binder. If any leaf 10 is swung about the axis of the binder, for example when opening out a pad or copybook or catalogue made of a number of such leaves thus bound, the portions of the leaves situated between their marginal perforations 19 cannot be moved beyond the plain portions or runs 16, 17 of the longitudinal edges of the strip 11 and cannot therefore penetrate into the notches 14, 15 and slide back through the slits 18. In other words, the leaves are locked in packed or bundled condition by the insertion of pairs of oppositely extending teeth or loops 12, 13 through their perforations 19. 1

An advantage of the notches 14, 15 which receive the free extremities of the teeth 12, 13 that are bent into loops to fulfil their leaf-binding function is that they enable said extremities to extend well beyond the adjacent edges of the 21 packed leaves, thus rendering the binding more secure. Another advantage of the notches 14, 15 is that by receiving and snugly accommodating the free extremities of the teeth or loops 12, 13 they prevent them from becoming turned or 25 shrivelled up particularly when a pack of leaves thus bound rubs a neighboring object. This obviates the risk of the extremities of the teeth 12, 13 becoming a cause of wound or injury.

Where, as in the embodiment shown in Fig. 5, 30 the narrow slits 18 between the contiguous teeth or loops 12, 13 in each pair extend helically to the major axis of the strip 11, the risk of an undue disengagement of the leaves 10 is still further lessened while the other qualities of the 35 binder are further enhanced.

The improved binder is applicable to packs or bundles of leaves or sheets made of paper, cardboard, thin metal or alloy, viscose and like products, Celluloid and analogous sheet form materials and particularly to all articles used in stationery or for teaching or advertising purposes such as copybooks, books, albums, diaries, catalogues, loose leaf pads; it is also adaptable to packed or bundled maps, charts, cards or similar articles. 45

The constructional details might vary of course without departing from the scope of the subjoined claims.

What is claimed is:

1. A binder for leaves provided with sets of aligned marginal perforations comprising a strip of resilient material having teeth extending from its opposite edges, said teeth being so positioned and curled in opposite directions as to 55 form pairs of oppositely convoluted resilient contiguous loops, a pair of said contiguous loops being sprung into each set of perforations, the free end of each tooth being adjacent the edge of the strip opposite to the edge whence said tooth extends. 60

2. A binder for leaves provided with marginal perforations comprising a strip of resilient material having spaced notches in its opposite longitudinal edges and teeth extending from the plain 65 portions of said edges, said teeth being so positioned and curled in opposite directions as to form pairs of oppositely convoluted resilient contiguous loops free of overlap, the pairs of said contiguous loops being sprung into the respective 70 perforations, the free end of each loop projecting into a notch in that edge of the strip opposite to the edge whence said loop extends.

3. A binder for leaves provided with marginal perforations comprising a strip of resilient mate- 75

rial having staggered notches in its opposite longitudinal edges and teeth extending from the plain portions of said edges between the notches, said teeth being so positioned and curled in opposite directions as to form pairs of oppositely convoluted resilient contiguous loops free of overlap, the pairs of said loops being sprung through the respective perforations, each loop being tapered and projecting into a notch of matching tapering shape in that edge of the strip opposite to the edge whence said loop extends.

4. A binder for leaves provided with marginal perforations comprising a strip of resilient material having staggered notches in its opposite longitudinal edges and teeth extending from straight portions of said edges between said notches, each tooth being narrower than the straight portion of the strip edge whence it extends, said teeth being curled in opposite directions to form pairs of oppositely convoluted resilient contiguous and nonoverlapping loops engaged through the respective perforations, each loop having a tapered outline and projecting with its free end into a notch in that edge of the strip opposite to the edge from which said loop extends.

5. A binder for leaves provided with marginal perforations comprising a strip of resilient material having staggered notches in its opposite longitudinal edges and integral teeth extending from straight portions of said edges between said notches, one edge of each tooth merging with the outline of a notch while the opposite edge of said tooth meets at an angle the adjacent straight portion of the strip edge, said teeth being curled in opposite directions to form pairs of oppositely convoluted resilient contiguous and non-overlapping loops, the pairs of contiguous loops being engaged through the respective perforations, each tooth being tapered and projecting into a notch in that edge of the strip opposite to the edge from which said tooth extends.

6. A binder for leaves provided with marginal

perforations comprising a strip of resilient material having staggered acute notches in its opposite longitudinal edges and integral tapering teeth extending from straight runs of said edges between said notches, one edge of each tooth being aligned with one side of a notch while the opposite edge of said tooth meets at an angle the adjacent straight run of the strip edge, said teeth being curled in opposite directions to form pairs of oppositely convoluted resilient adjacent loops, the contiguous edges of the loops in each pair running helically to the major axis of the strip, the pairs of adjacent loops being engaged through the respective perforations, the free end of each tooth deeply projecting into a notch in that edge of the strip opposite to the edge from which said tooth extends.

7. In combination with a pack of leaves provided with aligned marginal perforations, a binder comprising a strip of resilient material having teeth extending from its opposite longitudinal edges and so positioned and curled in opposite directions as to form pairs of oppositely convoluted resilient contiguous loops inserted through the respective perforations, the free end of each tooth being adjacent the edge of the strip opposite to the edge from which said tooth extends.

8. In combination with a pack of leaves provided with aligned marginal perforations, a binder comprising a strip of resilient material having spaced notches in its longitudinal edges and tapered teeth extending integrally and in staggered relation from its opposite edges, said teeth being so positioned and curled in opposite directions as to form oppositely convoluted resilient non-overlapping loops juxtaposed side by side pairwise and engaged through the respective perforations, the free end of each tooth projecting into a notch in the edge of the strip opposite to the edge from which said tooth extends.

ANDRÉ PRACHE.
